OSWALD W. KLINGSICK, OF RICHMOND HEIGHTS, MISSOURI, ASSIGNOR TO DAY-BRITE
REFLECTOR COMPANY, OF ST. LOUIS, MISSOURI, A CORPORATION OF MISSOURI

REFLECTOR SECURING MEANS

Application filed March 20, 1931. Serial No. 524,118.

My invention relates to means for securing channeled or troughed reflector members in the mounting troughs usually provided therefor. It has for its principal object to 5 simplify the means for mounting such reflector members.

In the accompanying drawing,

Fig. 1 is top plan view of a display construction having a reflector member securing 10 means embodying my invention,

Fig. 2 is a bottom plan view thereof with parts broken away to show one of my securing clips; and

Fig. 3 is a sectional view on the line 3—3 of 15 Fig. 1.

The reflector members of display lights for showcases and the like are ordinarily troughed members 1 of porcelain covered metal, in which reflector members are secured 20 electric lights 2 and their socket members 3.

Such reflector members 1 are ordinarily mounted in a metal or other channel-shaped support 4. According to the present invention, the means for securing such reflector in 25 the support comprises a plurality of straps or clips 5 having rebent end portions 6 engaging the edges of the reflector member and each having an interiorly threaded nut portion 7 through which extends a screw 8 whose 30 head portion is mounted in an inwardly extending sleeve 9 in the support 4. Rotation of said screw 8 in one direction causes it to pass through said nut portion 7 of the clip 5 to engage the reflector member 1 and force it 35 firmly into the rebent edges 6 of the clip and at the same time draws up the clip and reflector member tightly in the channeled support 4. The clip abuts against said sleeve 9 and engages the support 4 at one point 10, but is 40 otherwise clear of said support.

The reflector member 1 is smaller in all dimensions than the troughed support 4, so as to be spaced away therefrom at all points. Thus there is free circulation of air around 45 the reflector. Vent holes 11 may be provided in the support to permit escape of heated air.

The above described construction is very simple, eliminating numerous complicated positioning and fastening devices, commonly 50 required; and at the same time, it is very neat

in appearance and it holds the parts firmly together and permits separation thereof when required. It has the important advantage of holding the reflector member entirely out of contact with the mounting trough, 55 thereby minimizing heating of said mounting trough.

What I claim is:

1. A display light construction including a troughed support, a troughed reflector 60 member mounted therein and a securing clip for said reflector member having its ends supporting the edges of said reflector member, said securing clip having an interiorly threaded nut portion and a screw mounted in 65 said support and passing through said nut and engaging the surface of said reflector member.

2. A display light construction including a troughed support, a reflector member 70 mounted therein and spaced therefrom at all points and a securing clip for said reflector member having inwardly bent ends supporting the edges of said reflector member, said securing clip having an interiorly threaded 75 nut portion and a screw mounted in said support and passing through said nut and engaging the surface of said reflector member.

Signed at St. Louis, Missouri, this 17 day of March, 1931.

OSWALD W. KLINGSICK.
